(57) **CLAIM**

The ornamental design for a scale assembly for a fluid level gauge, as shown and described.

DESCRIPTION

FIG. 1 is a perspective view of a scale assembly for a fluid level gauge showing my new design;

FIG. 2 is a front elevational view thereof;

FIG. 3 is a top plan view thereof;

FIG. 4 is a bottom plan view thereof;

FIG. 5 is a side elevational view thereof;

FIG. 6 is a side elevational view thereof opposite that shown in FIG. 5; and,

FIG. 7 is a rear elevational view thereof.

The portion of the fluid level gauge shown in broken lines in FIG. 1 is for purposes of illustrating environment only and forms no part of the claimed design.

The scale assembly has been shown broken away in FIGS. 1, 2, and 5–7 to indicate indeterminate length.
